Application October 15, 1940, Serial No. 361,312

10 Claims.

(Cl. 270—5)

This invention relates to printing machines, and more particularly to improvements in method and means for propelling webs through the conventional web paths in modern rotary printing machines.

It has been the practice heretofore to drive the printing cylinders of the printing units at a given peripheral speed, and to progressively increase the peripheral speed of each "drag" or propelling roller as such roller is positioned beyond the first printing unit in the web path and towards the delivery portion of the machine. More specifically, each web is led from the usual web supply roll under the requisite tension and then through the printing unit or units. The printing cylinders of each printing unit are driven at a given peripheral speed and the web is guided in its path away from the unit, and travels at a linear speed substantially equal to the peripheral speed of the printing cylinders. One or more drag rollers may be positioned in the web path between a printing unit and the folder of the machine, and if more than one drag roller is employed, the first is driven at a peripheral speed slightly greater than the peripheral speed of the printing cylinders, and the next is driven at a still greater peripheral speed. The web is then led over a propelling roller, usually positioned above the folder former, and this roller is driven at a peripheral speed slightly greater than the greatest speed of the drag rollers. The web is then led over the folder former or formers and between one or more pairs of nipping rollers which are driven at a peripheral speed slightly greater than the propelling roller. The web is then cut and folded or otherwise discharged.

By progressively increasing the peripheral speed of the drag or propelling rollers, in the order in which such rollers are positioned in the web path beyond the printing unit or units, a taut web is insured, but it is manifest that some slippage must occur between the peripheral surfaces of the propelling or drag rollers and the running web. This slippage is somewhat difficult to control properly, and it is otherwise objectionable inasmuch as it tends to smut or tear the freshly printed web, and furthermore the relative movement between the peripheral surface of the roller and the web tends to reduce the frictional traction between the roller surface and the web, thus obviating the possibility of obtaining the positive control that can be produced by driving the roller at web speed. If each propelling or drag roller, however, is positively driven at web speed, any slack that may be present initially or may occur

between the printing unit or units and the drag roller, or between the drag roller and subsequent propelling rollers could not be taken up. Consequently, it is necessary in existent positive drives 5 that the drag and propelling rollers be driven at progressively increased speeds as they are positioned towards the delivery portion of the machine.

The propelling roller and nipping rollers provided for the former are so located that they may be positively driven from the press drive, inasmuch as driving connections are available at this point. But even so, the positive driven rollers must be driven at peripheral speeds greater than 15 web speed, in order to prevent slackness in the web, as hereinbefore pointed out.

It is, therefore, an object of this invention to provide improved method and means for driving each drag roller, propelling roller or nipping 20 roller of a rotary printing machine through an independent drive instrumentality which causes the roller to conform to web speeds but to exert a constant torque pull on the web, which torque pull is so controlled as not to exceed the frictional 25 resistance existent between the roller surface and the web, thus avoiding any slippage between the roller surface and the web.

Another object of this invention is to provide improved method and means for driving each 30 drag roller, propelling roller or nipping roller in the web path of the printing machine through an independent drive which causes each roller to conform to web speed but to exert a constant torque pull on the web, this torque pull being 35 controlled so that it does not exceed the frictional resistance existent between the roller surface and the web, thus avoiding any slippage between the roller surface and the web, the torque pull being constant throughout the range of accelerating speeds and also at starting and during the running period.

A further object of this invention is to provide 40 an electric torque motor for driving each drag roller or other web propelling roller at a speed 45 which conforms to web speed, the roller maintaining a torque pull on the web which is substantially constant at starting and running speeds and throughout the range of accelerating speeds of the roller, the electric current for the motor being supplied through a motor generator set and a press driven generator electrically connected in suitable electric circuits.

It is also an object of this invention to provide 50 improved web propelling means for printing machines, which include an independent electric

torque motor for driving each drag roller of the printing machine, and independent mechanically-driven yieldable drives or connections for each propelling roller or nipping roller of the machine, each roller being so driven that its peripheral speed conforms to the web speed but exerts a constant torque pull on the web, the torque of the roller being so controlled as not to exceed the frictional resistance existent between the roller surface and the web, thereby avoiding any slippage between the roller surface and the web.

With the foregoing and other objects in view, which will appear as the description proceeds, the invention resides in the combination and arrangement of parts and in the details of construction hereinafter described and claimed, it being understood that various changes in form, proportion, and minor details of construction may be made within the scope of the claims without departing from the spirit or sacrificing any advantages of the invention.

For a complete description of the invention, a detailed description of the improved method and means for driving printing machine web propelling rollers will now be given in connection with the accompanying drawings forming a part of the specification wherein:

Figure 1 is a diagrammatic side view of a printing machine, showing a preferred form of the invention applied thereto;

Figure 2 is a diagrammatic plan view;

Figure 3 is a diagrammatic plan view of a printing machine showing a modified form of the invention applied thereto;

Figure 4 is a fragmental diagrammatic side view thereof;

Figure 5 is a longitudinal sectional view taken through a yieldable drive unit;

Figure 6 is an end view thereof;

Figure 7 is an electrical diagram of the circuits supplying current to the torque motors; and

Figure 8 is a plan view of one motor driving geared nipping rollers.

Referring to the drawings in which similar reference characters designate corresponding parts, in Figures 1 and 2, there is depicted, in diagrammatic form, a quadruple printing press which includes a base 10 that supports the usual frame components 11 for a folder F. The printing units, and the web guides, in conformity with the usual practice, have suitable frame members, not shown, which are supported on the base. Rotatably supported at one terminal of the base 10 are a plurality of web supply rolls 12, and the web W from the upper rolls 12 is led over and around guide rollers 13 to and through the first perfecting printing unit A. The printing unit A is of conventional construction and includes a plate or form cylinder 15 which cooperates with an impression cylinder 16 to print one side of the web, and a second plate or form cylinder 17 which cooperates with a second impression cylinder 18 to "perfect" or print the other side of the web. The perfected web is then led from the printing unit A over guide rollers 20 to a drag or web propelling roller 21. The web W may now be slit into separate ribbons R and R1, and the ribbon R is led over and around guide rollers 22 to a second drag roller or web propelling roller 23 located adjacent and above the former f of the conventional folder F. The ribbon R1 may be diverted from its path of travel by passing it over and around turner bars 25, so that it is positioned immedi-

ately below the web R, and then it is led over and around guide rollers 26 to the drag or propelling roller 23.

The web W' from the lower web supply roll 12 is led over and around guide rollers 27 to and through the second perfecting printing unit B, which unit is of conventional construction and is similar to unit A. After passing through the unit B, the web W' is led over and around guide roller 28 to a drag or web propelling roller 30. The web W' may now be slit into separate ribbons R2 and R3, and the ribbon R2 is led over and around guide rollers 31 to the drag or propelling roller 23. The ribbon R3 may be diverted from its path of travel by passing it over and around selected turner bars 25, so that it is positioned immediately below the web R, and then it is led over and around guide rollers 32 to the drag or propelling roller 23.

Pressure rollers 34 may be supported in running engagement with the webs, to press them against the drag or propelling rollers 21, 23 and 30 and insure that the web is properly driven. In accordance with well known practice, the supports for these rollers are provided with suitable adjusting mechanism not shown, whereby their pressure on the web may be varied as required.

The four ribbons are led down over the former f to produce the conventional longitudinal fold, and they are then engaged by opposed web propelling or nipping rollers 33, and then the ribbons are conveyed through the folding cylinders, not shown, to the usual delivery mechanism, and finally delivered as finished products.

In the described arrangement, it is assumed that four ribbons are passed down over one former, but of course, this is merely one of the many possible arrangements, and, if preferred, the webs may be slit and then so conveyed that one, two or more ribbons pass downwardly over each former, but in either event, the webs are propelled by the drag rollers 21 and 30, and the ribbons are propelled by the drag or propelling roller 23 and the nipping or web propelling rollers 33.

In the arrangement shown in Figures 1 and 2, the printing units A and B are driven from the line shaft S by suitable conventional drive instrumentalities. Each printing unit is provided with a vertical drive shaft 35 which is driven from the line shaft S through meshing bevel gears 36 and 37. The vertical shaft 35 of each printing unit drives a bevel gear 38 which meshes with a similar gear 40, which rotates with a helical or straight spur gear 41, and this gear 41 meshes with a similar gear 42 which rotates with the plate or form cylinder 17. The gear 42 meshes with a similar gear 43 which rotates with the impression cylinder 18, thus driving the plate and impression cylinders 17 and 18 in unison. The gear 41 also meshes with a gear 45 which rotates with the impression cylinder 16, and the gear 45, in turn, meshes with a similar gear 46 which rotates with the plate cylinder 15, thus causing the plate and impression cylinders 15 and 16 to rotate in unison. While in the depicted arrangement, only two printing units are indicated, it is to be understood, of course, that any preferred number of such units may be provided, and each unit is positively driven from the line shaft S through the instrumentalities herein disclosed.

It has been the practice heretofore to positively drive the web propelling rollers through suitable drive instrumentalities or connections

which are driven from the press drive shaft S, and these web propelling rollers are so driven that the speed of each roller, as it is positioned away from the printing unit and towards the delivery terminal of the press, is progressively increased. Such arrangement insures the taking up of any slack that may occur in the web in threading the press, but it also necessitates some slippage between the roller surface and the web, under all running conditions, and the difference between the speed of the roller and that of the web tends to smut or tear the freshly printed web. Furthermore, the setting of the pressure rollers 34 requires delicate adjustment, and it is also troublesome.

The drag or web propelling rollers 21 and 30 are so located that it is both expensive and inconvenient to positively drive them from existent drive instrumentalities of the machine, because no suitable drive shafts are available at this location. In addition to the great expense entailed in positively driving these rollers, there still remains the objections hereinbefore stated.

In order to avoid the objectionable phases incident to the provision of mechanical drives for web propelling rollers, this invention contemplates the provision of means for individually driving each web propelling roller by a separate yieldable drive instrumentality which permits the roller surface to conform to web speed and constantly maintain uniform torque pull on the web. In the arrangement depicted in Figures 1 and 2, an electric torque motor 50 is directly connected through an interposed shaft 51 with each web propelling roller 21, 23, 30 and 33. The motors 50 for the drag and web propelling rollers 21, 23 and 30 are located at one side of the machine. These motors may be suitably supported on any convenient component of the machine frame. Inasmuch as the nipping or web propelling rollers 33 are arranged in pairs in which one roller is located immediately adjacent the other to engage the folded web, their motors 50 are preferably positioned at opposed terminals of each pair of the cooperating rollers 33 in order to avoid crowding or interference of the motors. While a separate motor is shown for each nipping roller 33, it will be understood that, if desired, each pair of nipping rollers 33 may be geared together by suitable intermeshing gears 33a and driven by a single motor, as diagrammatically indicated in Figure 8.

The requisite voltage is applied to each motor so that the desired torque will be constantly maintained at starting and all running speeds, and also, throughout the accelerating range up to top speed. This is accomplished by instrumentalities that will be hereinafter more fully disclosed. The webs in passing through the printing units are tightly engaged between the form and impression cylinders of these units, so that the web travels at a linear speed substantially equal to the peripheral speeds of these cylinders. After leaving the printing units, the web is then engaged by guide rollers and propelling rollers, and each propelling roller is driven at a speed potentially greater than the linear speed of the web, but the peripheral speed of each propelling roller is restrained to the linear speed of the web by the frictional engagement between the roller surface and the web, thus producing a constant torque pull on the web. This torque is so controlled that it does not exceed the frictional resistance existent between the peripheral surface of each web propelling roller and the web, thus

insuring that the roller surface and the web travel at the same speed, although the roller is constantly urged toward a higher speed by being driven at a potential peripheral speed greater than the linear speed of the web. By this arrangement, a more positive control is insured at each propelling point, and, furthermore, the web will not slip on the roller surface and smut or tear the freshly printed web. Inasmuch as the propelling roller surface and the web travel at the same speed, there is no relative movement to break the frictional resistance set up at this point, thus insuring the maximum propelling action or drag for each web propelling roller.

15 In the form of the invention disclosed in Figures 3, 4, 5 and 6, the press units A and B are driven from the line shaft S, and the web propelling or drag rollers 21 and 30 are driven by the torque motors 50, as hereinbefore disclosed in the description of the form of the invention shown in Figures 1 and 2. If preferred, however, the rollers 21 and 30 may be driven from the line shaft S through slip or torque clutches to be hereinafter described. The web propelling rollers 23 and 33, are preferably driven by mechanically connecting them with the line shaft S through the yieldable or slip clutches, as herein-after disclosed.

Referring to Figures 3 and 4, it will be observed that the press drive or line shaft S, in addition to driving the printing units A and B, through the instrumentalities hereinbefore disclosed, also carries a bevel gear 55 which meshes with a similar gear 56. The gear 56 is carried by a vertical shaft 57 which is rotatably supported in conventional bearings, not shown, adjacent the folder F. The shaft 57, at a point intermediate its terminals, carries a bevel gear 58 which meshes with a similar gear 60 supported at one terminal of a horizontal transversely-disposed shaft 61. The shaft 61 carries four bevel gears 62 which mesh with similar gears 63, and each gear 63 is carried at the outer terminal of a stub shaft 65. As best shown in Figures 5 and 6, the inner terminal of each stub shaft 65 is rotatably received within a bearing 66 formed in one terminal of a clutch housing 67 of a slip or torque clutch device 64. A clutch flange or head 68 is suitably secured to the inner terminal of each shaft 65, and the hub or sleeve 70 of this flange engages an antifriction thrust bearing 71, which, in turn, engages the inner terminal of the bearing 66 to thereby receive any thrust load that may be imparted to the clutch face 72 of the flange 68. A collar 73 is pinned or otherwise secured to the shaft 65, and engages the outer terminal of the bearing 66 to thereby cooperate with the flange sleeve 70 and thrust bearing 71 to hold the shaft 65 against longitudinal movement relative to the bearing 66 and housing 67. A shaft 75 is rotatably received in a bearing 76 formed at the opposed terminal of the clutch housing 67, and this shaft 75 is held against longitudinal movement relative to the bearing 76 and housing 67 by spaced collars 77 which are pinned or otherwise secured to the shaft 75. The hub or sleeve portion 78 of a clutch flange or head 80 is mounted on the shaft 75 for longitudinal movement relative thereto, but it is held against rotary motion relative to the shaft 75 by a key or other securing instrumentality 81. Clutch discs 82 are secured to the clutch faces of the clutch flanges 68 and 80 and are held in yielding engagement with each other by a helical spring 83 which surrounds the sleeve or hub 78 of the clutch head

80. One terminal of this spring engages the flange of the clutch head 80, and the opposed terminal engages an antifriction thrust bearing 85 which is slidably mounted on the clutch sleeve 78. A bifurcated arm 86 straddles the clutch sleeve 78, and its bifurcated portion engages the outer face of the thrust bearing 85. The arm 86 is keyed or otherwise rigidly secured to a shaft 87 which is rotatably received in bearing apertures 88 formed in the clutch housing 67. The shaft 87 extends outwardly beyond the housing, and the sleeve or hub 90 of an actuating finger 91 is pinned or otherwise rigidly secured to the shaft 87. A lug or ear 92 extends outwardly from the clutch housing 67 and is provided with a threaded aperture which receives a threaded stem 93 carried by a hand or manipulating wheel 95, and the inner terminal of the threaded stem engages the outer face of the actuating finger 91. By this arrangement, the tension on the spring 83 may be readily adjusted by rotating the manipulating wheel or handle 95 to thus predetermine the pressure with which the clutch discs 82 engage each other.

The clutch housing is preferably filled with oil, grease or suitable lubricant, and the hand wheel or handle 95 is manipulated to produce the requisite frictional engagement between the clutch discs 82 carried by the clutch flanges 68 and 80. By this arrangement, the rotating stub shaft 65 of each clutch device 64 imparts the requisite torque to the shaft 75, for a purpose to be hereinafter disclosed. In this form of the invention, each nipping roller or web propelling roller 33 is secured to a shaft 75 so that the roller is driven through the slipping clutch device. In Figure 3, a separate clutch device 64 is shown for each roller 33, but it will be understood that each pair of rollers 33 may be geared together as hereinbefore stated, and that a single clutch device may be employed to drive both, as indicated in Figure 8.

A bevel gear 100, shown in Figures 3 and 4, is secured to the upper terminal of the shaft 57, and this gear meshes with a bevel pinion 101 carried by a longitudinally extending horizontal shaft 102 which carries a bevel gear 103. The bevel gear 103 meshes with a bevel pinion 105, and the pinion 105 is secured at the outer terminal of a shaft 65 of a selected slipping clutch device 64. The opposed shaft 75 of this slipping clutch device 64 is secured to the web propelling or drag roller 23 to thereby drive this roller with the requisite torque, which torque is controlled through the slipping clutch device 64, as hereinbefore disclosed. The slipping clutch devices may be secured to the machine frame in any suitable or preferred manner, and inasmuch as such mountings are well known and understood by those skilled in the art, they have, for the sake of simplicity, been omitted in the drawings.

In this form of the invention, the printing units A and B are driven from the drive or line shaft S, and, as hereinbefore pointed out, the peripheral speed of the cylinders of the printing units control the linear speed of the webs and ribbons. Each drag roller 21 and 30 is individually controlled by a torque motor 50, as hereinbefore stated, and the drag or web propelling roller 23 and the nipping or web propelling rollers 33 are each controlled by a slipping clutch arrangement 64, and, inasmuch as the torque imparted through each slipping clutch can be adjustably controlled to the requisite degree, it is manifest that the rollers 23 and 33 rotate with the web without slip-

page, but exert the requisite torque pull on the webs or ribbons. In this form of the invention, the slipping clutch devices 64 drive the rollers 23 and 33 instead of the torque motors, because, at this location, drive instrumentalities are available.

Inasmuch as mechanical driving connections are not available for the drag rollers 21 and 30 unless the necessary gears and shafting to connect them with the shaft S are provided, in most printing machines these rollers are preferably driven by independent torque motors 50. It is obvious, however, that if driving connections on the machine are available, a slipping clutch device 64 may be employed to drive each of the drag rollers 21 and 30.

In arrangements where the web propelling and nipping rollers 23 and 33 are positively driven from the press drive, in conformity with previous practice, these drives are effected through instrumentalities similar to those disclosed in Figure 3, except that the slipping clutches 64 are not employed, but, in such arrangements, it is necessary, as hereinbefore stated, to drive the rollers 23 and 33 at speeds slightly in excess of web speed, and the speed of each roller is progressively increased as it is positioned towards the delivery terminal of the machine.

Where propelling rollers are driven by independent electric torque motors 50, the torque on each motor is automatically controlled so that it will impose the desired pull on the web. This is accomplished by providing the proper voltage to each torque motor so that the desired torque will be substantially constant at starting and all running speeds, that is, there must be adequate torque imposed on the motor before it starts to move, and also throughout its accelerating range up to top speed and during running speed. This is accomplished by the provision of a motor generator set and one or two press driven generators, as indicated in the diagrammatic Figure 7, and which will be more fully disclosed hereinlater. The press driven generator supplies the greater part of the electric power required to drive the torque motors 50 for the drag or web propelling rollers, and the voltage of this generator, which is shunt wound, will vary substantially in proportion to press speed. The constant speed generator of the motor generator set will preferably generate about 10% of the voltage generated by the press driven generator when the press is running at full speed. Thus it is to be understood that 10% of the full voltage is imposed on the motor before the press starts and provides the requisite torque to insure proper web tension in starting. Thereafter the press driven generator voltage increases as the press accelerates, and the torque motor receives a corresponding increased voltage thereby increasing the speed and torque proportionately. In the preferred arrangement, as herein disclosed, a second small generator is provided that is driven at constant speed, and the armature of this generator is in series with the field of the main generator and tends to iron out or equalize what would otherwise be a hump in the voltage curve. Where less accurate regulation is satisfactory, the second small generator may be omitted.

Referring to diagrammatic Figure 7, 110 indicates a 110 volt D. C. generator directly connected to the printing machine, and, consequently, driven at variable speeds, which speeds are proportionate to the speed of the machine. A motor generator set is provided and includes a con-

stant speed motor 111 which is driven from any convenient circuit, and this motor drives generators 112 and 113 independently of the printing machine drive. The torque motors 50, as hereinbefore disclosed, are directly connected with the web propelling roller.

While the current supplied and generated may be commensurate with the load requirements, we may assume, for sake of illustration, that the generator 110 is of one kilowatt capacity, 110 volts; generator 112 of 200 watts capacity, 15 volts; and generator 113 of 50 watts capacity, 10 volts. The web propelling torque motors may be of one-fourth horse power capacity.

A direct current circuit is provided, which may be of 110 volts potential, and the positive lead of the circuit is indicated at 115 and the negative lead at 116. The shunt field 117 of the machine driven generator 110 receives its energy from this circuit, and this field is connected with the positive lead 115 of the circuit through lead 118. Generator 113 has its armature connected in series with the field 117 of generator 110 through leads 120 and 121, but it is connected in opposition to the line voltage, as indicated, to "buck" its potential, in order to effect the desired automatic regulation of the voltage supplied to the armatures of the motors 50.

The shunt fields of the motors 50 are energized from the 110 volt lines 115 and 116 through leads 122 and 129. Generator 110, as stated, supplies most of the current for the armatures of the torque motors 50, through leads 123 and 125, but it is assisted by the generator 112, the armature and series field of which are in series with the armature of generator 110, as indicated, and impresses a potential of approximately 15 volts on the circuit to the torque motors 50 to produce torque before the printing press starts, and this voltage is added to the voltage generated by the generator 110 when the machine is in operation. A rheostat 128 is connected in series with the shunt field of the generator 112 and provides means for regulating the voltage supplied by this generator.

The field of the generator 113 is also in series with the output circuit of generator 110 as indicated, and the amount of current flowing in this circuit consequently determines the voltage of generator 113.

As is usual in machines of this class, generator 110 has a disproportionate change in voltage with small changes in speed in the higher speed range than it has in the lower speed range. In consequence, if the arrangement is such that it generates the proper voltage at low press speeds, it will generate excessive voltage at the higher press speeds. While this change is not abrupt, and it is tapered over the range, it may be objectionable in some cases, and this objection may be overcome by the use of the generator 113, for it will be understood that the field of generator 113 will receive more current at high press speeds and thus produce greater bucking effect, thereby reducing the field current of generator 110 and accomplishing the desired regulation automatically.

A rheostat 127 is connected in parallel with the shunt field winding of motor 113 and provides means for regulating the voltage generated by its armature, which as indicated above, reacts on the field of generator 110.

From the foregoing, it will be seen that the fields of motors 50 are connected across a constant voltage, while their armatures are con-

nected across a voltage that varies, depending upon the speed of the printing machine, but even when the machine is stopped, the motors 50 are subjected to voltage generated by the motor 112, and the motors 50 therefore produce a constant torque on the web propelling rollers to which they are connected, at all press speeds. With the several generators proportioned and arranged as shown, the torque produced by the armatures of the motors 50 will be substantially constant from zero to maximum printing machine speed.

The several rheostats shown permit regulation to obtain the proper balance in the effectiveness of the several generators, and may be adjusted as desired to provide for as many motors 50 as may be connected for operation.

While the arrangement described herein shows but one pair of nipping rollers 33, it is quite common practice at the present time to use two pairs of these rollers, one pair mounted immediately above the other pair below each former. It will, therefore, be understood that two pairs of rollers 33 through which the same web passes may be driven by either the torque motor arrangement 50 or the clutch devices 64, and, alternatively, the lower of the two pair of rollers may be driven by clutch devices 64, while the upper rollers are provided with torque motor drives. This latter arrangement is particularly advantageous where it is desirable to simultaneously adjust the former and the nipping rollers adjacent same transversely with respect to the run of the web as is done in some cases. In such case, the clutch drive for the lower pair of rollers 33 is preferred because of their proximity to the folding cylinders.

While the drawings and the foregoing description show the invention applied to a printing machine equipped with a folder, it will be evident to those versed in the art that the invention is equally applicable to machines in which products are delivered in sheet form and without being folded.

It will be understood that the invention may be embodied in other specific forms without departing from the spirit or essential attributes thereof, and it is therefore desired that the present embodiment be considered in all respects as illustrative and not restrictive, and it will be further understood that each and every novel feature and combination present in or possessed by the mechanism herein disclosed forms a part of the invention included in this application.

Having thus described my invention, what I claim as new and useful is:

1. The method of propelling a web through a printing machine having a printing couple, a folder having a former, a propelling roller located operably ahead of the former and nipping rollers located operably after the former, which consists in feeding the web through the printing couple and the folder at a linear speed which substantially equals the peripheral speed of the cylinders of the printing couple, interposing a drag roller between the printing couple and the folder propelling roller, the drag roller, propelling roller and nipping rollers gripping the web to prevent slip to propel the web from the printing couple to and over the former, and yieldingly driving the drag roller, the folder propelling roller and nipping rollers for a potential peripheral speed greater than the linear speed of the web to exert a torque pull on the web, controlling the torque pull of each roller so as not to exceed the grip between the web and the roller to thereby re-

strain the peripheral speed of the roller to the linear speed of the web by the grip between the web and the roller.

2. The method of propelling a web through a printing machine having a printing couple and a former folder driven by the machine drive, a propelling roller located operably ahead of the former of the folder, and nipping rollers located operably after the former, which consists in feeding the web through the printing couple and folder at a linear speed which substantially equals the peripheral speed of the cylinders of the printing couple, interposing a drag roller between the printing couple and the folder propelling roller, each roller gripping the web to prevent slip, driving each roller which is operably accessible to the machine drive through a slip clutch which is driven by the machine drive for a potential speed greater than the linear speed of the web to exert a torque pull on the web, and driving each roller which is inaccessible to the machine drive by an electric torque motor for a potential speed greater than the linear speed of the web to exert a torque pull on the web, and controlling the torque pull of each roller so as not to exceed the grip between the web and the roller to thereby restrain the peripheral speed of the roller to the linear speed of the web by the grip between the web and roller.

3. The method of propelling a web through a printing machine having a printing couple and a former folder driven by the machine drive, a propelling roller located operably ahead of the former of the folder and nipping rollers located operably after the former, which consists in feeding the web through the printing couple and the folder at a linear speed which substantially equals the peripheral speed of the cylinders of the printing couple, interposing a drag roller between the printing couple and the folder propelling roller, each roller gripping the web to prevent slip, driving the drag roller by an electric torque motor, and driving the folder propelling roller and nipping rollers from the machine drive through slip clutches for a potential peripheral speed greater than the linear speed of the web to exert torque pull on the web, controlling the torque pull of each roller so as not to exceed the grip between the web and the roller to thereby restrain the peripheral speed of the roller to the linear speed of the web by the grip between the web and the roller.

4. The method of propelling a web through a printing machine having a printing couple, a folder having a former, a propelling roller located operably ahead of the former and nipping rollers located operably after the former, which consists in feeding the web through the printing couple and the folder at a linear speed which substantially equals the peripheral speed of the cylinders of the printing couple, interposing a drag roller between the printing couple and the folder propelling roller, the drag roller, propelling roller and nipping rollers gripping the web to prevent slip to propel the web from the printing couple to and over the former, driving each roller by an electric torque motor for a potential peripheral speed greater than the linear speed of the web to exert a torque pull on the web, controlling the torque pull of each roller so as not to exceed the frictional grip between the web and the roller to thereby restrain the peripheral speed of the roller to the linear speed of the web by the grip between the web and the roller.

5. The method of propelling a web through a

printing machine having a printing couple, a folder having a former, a propelling roller located operably ahead of the former and a pair of cooperating nipping rollers located operably after the former, which consists in feeding the web through the printing couple and the folder at a linear speed which substantially equals the peripheral speed of the cylinders of the printing couple interposing a drag roller between the printing couple and the folder propelling roller, the drag roller, propelling roller and the nipping rollers gripping the web to prevent slip to propel the web from the printing couple to and over the former, operably connecting the cooperating nipping rollers so that they rotate in unison, driving the drag roller, the propelling roller and the pair of cooperating nipping rollers by a separate electric torque motor for a potential peripheral speed greater than the linear speed of the web to exert a torque pull on the web, controlling the torque pull of the drag roller, the propelling roller and the cooperating pair of nipping rollers so as not to exceed the grip between the web and the rollers to thereby restrain the peripheral speed of the rollers to the linear speed of the web by the grip between the web and the rollers.

6. The method of propelling a web through a printing machine having a printing couple, a former folder driven by the machine drive, a propelling roller located operably ahead of the former of the folder and nipping rollers located operably after the former, which consists in feeding the web through the printing couple and the folder at a linear speed which substantially equals the peripheral speed of the cylinders of the printing couple, interposing a drag roller between the printing couple and the folder propelling roller, each roller gripping the web to prevent slip to propel the web from the printing couple to and over the former, driving each roller from the machine drive through a friction slip clutch for a potential peripheral speed greater than the linear speed of the web to exert torque pull on the web, controlling the torque pull of each roller so as not to exceed the grip between the web and the roller to thereby restrain the peripheral speed of the roller to the linear speed of the web by the grip between the web and the roller.

7. The method of propelling a web through a printing machine having a printing couple and a former folder driven by the machine drive, a propelling roller located operably ahead of the former of the folder and a pair of cooperating nipping rollers located operably after the former, which consists in feeding the web through the printing couple and the folder at a linear speed which substantially equals the peripheral speed of the cylinders of the printing couple, interposing a drag roller between the printing couple and the folder propelling roller, each roller gripping the web to prevent slip to propel the web from the printing couple to and over the former, operably connecting the cooperating nipping rollers so that they rotate in unison, driving the drag roller, the propelling roller and the pair of cooperating nipping rollers from the machine drive through a friction slip clutch for a potential peripheral speed greater than the linear speed of the web to exert torque pull on the web, controlling the torque pull of the drag roller, the propelling roller and the pair of cooperating nipping rollers so as not to exceed the frictional grip between the web and the rollers to thereby restrain the peripheral speed of each roller to the linear

speed of the web by the grip between the web and the rollers.

8. In a rotary web printing machine having rotary printing cylinders, a delivery and a machine drive, a web forwarding roller between the printing cylinders and delivery and which grips the web, a frictionally driven slip clutch operably interposed between the machine drive and the web forwarding roller to drive said roller, the clutch including a closed housing, a drive member operably connecting with the machine drive and having a friction clutch face rotatable within the housing, a driven member operably connected with the web forwarding roller and having a friction clutch face rotatable within the housing and arranged for cooperable engagement with the driven friction clutch face, means for biasing the driven clutch face into frictional engagement with the drive clutch face, and means adjustable from a point outside of the housing to vary the degree of bias exerted by the driven clutch face against the drive clutch face.

9. In a rotary web printing machine having printing cylinders and a delivery, a web forward-
ing roller between the printing cylinders and the

5 delivery and against which the web is pressed, an electric motor to drive the roller, a first generator driven in timed relation with the printing machine to supply current to the motor, a second generator driven at constant speed to assist in supplying current to the motor, and a third generator to regulate the voltage of the first generator, whereby the roller is driven for a potential peripheral speed slightly higher than that 10 of the printing cylinders and maintains a substantially constant forward pull on the web.

10. In a rotary web printing machine having printing cylinders and a folding mechanism with cooperating nipping rollers frictionally gripping the web, an electric motor controlled by the speed of the machine and arranged to drive each nipping roller for a potential peripheral speed slightly higher than the speed of the printing cylinders by imparting torque to the roller of a 15 value not to exceed the frictional grip between the web and the rollers to thereby restrain the peripheral speed of the rollers to the printing cylinder speed.

WILLIAM F. HUCK.
